UNITED STATES PATENT OFFICE.

OSCAR JOHNSON, OF BOVEY, MINNESOTA.

MECHANICALLY-ACTUATED HAMMER.

1,174,988.

Specification of Letters Patent. Patented Mar. 14, 1916.

Application filed April 19, 1915. Serial No. 22,461.

To all whom it may concern:

Be it known that I, OSCAR JOHNSON, a citizen of the United States, residing at Bovey, in the county of Itasca and State of Minnesota, have invented certain new and useful Improvements in Mechanically-Actuated Hammers, of which the following is a specification.

This invention relates to mechanically actuated hammers and it has for its object the provision of an improved device of this character comprising a pair of hammers together with a sliding element arranged to engage said hammers and cause them to alternately strike upon an anvil interposed between them.

It is a further object of the invention to utilize the driving means of the hammers for imparting motion to a grindstone or emery-wheel when desired.

Further objects and advantages of the invention will be set forth in the detailed description which now follows.

In the accompanying drawing: Figure 1 is a side elevation of a mechanically actuated hammer constructed in accordance with the invention. Fig. 2 is a plan view thereof. Fig. 3 is a detail perspective view, and Fig. 4 is a modification.

Like numerals designate corresponding parts in all of the figures of the drawing.

Referring to the drawing, the numeral 5 designates an elongated bed-plate supported upon base pieces 6. Centrally arranged upon the bed-plate 5 is an anvil of the peculiar form shown, comprising an intermediate body portion 6^a, side plates 7, horn 8 and a removable striking surface 9, having depending side-plates 10 which are arranged to embrace the body 6^a of the anvil. Sliding beneath the body of the anvil and disposed between the side-plates 7 thereof is a sliding-plate 11 held in place by keepers 12. This plate 11 is provided with upstanding abutments 13 recessed as at 14 and having openings 15 formed therein. It will be noted that the bottoms of the recesses 14 are inclined, the purpose of which it is apparent is to conform to the position in which the hammers lie when they are raised (see Fig. 1). The hammers are indicated at 16 and 17. They are provided with bent helvæ 18 and 19 and are pivotally connected at 20 and 21 to the bed-plate 5. When the sliding-plate 11 is moved in one direction the vertical walls 22 at the inner ends of the slots

15 act to raise the hammers to the position in which the hammer 17 lies in Fig. 1, at which time the rear edge of the hammer helvæ rests upon the inclined bottom of the recess 14. When the plate 11 is moved in the opposite direction the nose 23 at the opposite end of the recess acts to throw the hammer over and strike a blow upon the anvil. For imparting reciprocatory move-

ment to sliding-plate 11 a connecting rod 24 is pivoted at 25 to the plate 11 and at its opposite end is pivoted to a crank 26 of a shaft 27 that is mounted in bearings 28. This shaft carries a pulley 29, a disk 30 and a pulley 31. The disk 30 is provided with a crank handle 32 by which the shaft may be rotated by hand or it is apparent that if it be desired to drive the device by power, a belt, not shown, may be applied to pulley 29. A belt 33 passes over the pulley 31 and over a pulley 34 that is carried by a shaft 35. The shaft 35 is mounted in bearing standards 36 and carries an emery-wheel 37 and a grindstone 38. The bearing standards 36 are carried by a sliding block 39 which passes beneath the bed-plate 5. A plate 40 spans the space between the bearing standards and lies above bed-plate 5 by virtue of which construction the bearing standards are slidably mounted with relation to the bed-plate 5 and when moved away from shaft 27 it is apparent that the belt 33 will be tightened. For thus moving the bearing standards 36 a lever 41 is pivoted at 42 in a cut-out portion 43 of the bed-plate 5 and a link 44 is connected to this lever and to the plate 40 so that when the handle is swung rearwardly or to the left, in Fig. 1, the belt 33 will be tightened. A wire 45 bent to substantially U shape pivoted at 46 upon the bed-plate 5 acts as a pawl by engaging a notch 47 of lever 41 to hold this lever in position to keep the belt tightened during the time that it is desired to use either the emery-wheel 37 or the grindstone 38. A well or like receptacle 48 is carried by the block 39 and the lower edge of the grindstone depends therein. A hand grip 50 is pivoted at 51 upon the lever 41 and carries depending ends 52 arranged to engage and throw the wire pawl 45 out of the notch 47 when it is desired to release the slidably mounted bearings 36 to loosen the belt 33.

The pivots 20 and 21 are composed of transversely extending rods which have braces 53 engaged therewith which braces

extend upwardly and engage the hammer helvæs at 54, then bent into engagement with each other at 55 and pass through the hammer heads at 56 by virtue of which the necessary guiding action for the hammers is secured.

The modified device shown in Fig. 4 is like that shown in the remaining figures except that springs E, F are secured at the opposite ends of the slot 15 of bar 11 to cushion the action of the hammers.

While the elements shown and described are well adapted to serve the function for which they are intended, it is to be understood that the invention is not to be limited to the precise construction set forth, but that it includes within its purview whatever is new that comes within the spirit of the appended claims.

Having described my invention, what I claim is:—

1. In a device of the character described, the combination with a pair of pivotally mounted hammers, an anvil disposed between them, a slidably mounted plate engaging said hammers in such manner as to impart simultaneous swinging movement to them when reciprocated, thus causing them to alternately coöperate with the anvil, and means for reciprocating said plate.

2. In a device of the character described, the combination with a bed-plate, an anvil carried thereby, a pair of hammers having bent helvæs pivoted to said bed-plate, said anvil being located between said hammers, a slidably mounted plate having openings therein through which the helvæs of said hammers pass, and means for imparting reciprocation to said slidably mounted plate.

3. In a device of the character described, the combination with a bed-plate, of hammers having bent helvæs, the ends of which are pivoted to said bed-plate, an anvil located in position to be struck by said hammers, a slidably mounted plate having open-

ings therethrough, through which the helvæs of said hammers pass and guiding and bracing means connected to the hammer helvæs and engaging the pivots of the hammers outside of said bed-plate.

50

4. In a device of the character described, the combination with a bed-plate, of hammers having bent helvæs, the ends of which are pivoted to said bed-plate, an anvil located in position to be struck by said hammers, a slidably mounted plate having openings therethrough, through which the helvæs of said hammers pass and guiding and bracing means connected to the hammer helvæs and engaging the helvæs of said hammers 55 and the heads of said hammers.

55

5. In a device of the character described, the combination with a bed-plate, a pair of hammers having bent helvæs pivoted thereto, an anvil carried thereby and disposed 65 between said hammers, a slidably mounted plate, there being openings formed through said plate having substantially vertical inner walls and having inclined portions at their outer ends substantially as shown and 70 described.

6. In a device of the character described, the combination with a bed-plate, an anvil carried thereby, a pair of hammers having bent helvæs pivoted to said bed-plate, said 75 anvil being located between said hammers, a slidably mounted plate having openings therein through which the helvæs of said hammers pass, means for imparting reciprocation to said slidably mounted plate, and 80 springs carried by said slidably mounted plate for cushioning the action of said hammers.

In testimony whereof I affix my signature in presence of two witnesses.

OSCAR JOHNSON.
